UNITED STATES PATENT OFFICE

165,856

TRANSPARENT CAPSULE AND TABLET POCKET CARRIER

Lee S. Mytinger, Long Beach, Calif., assignor of
one-half to Wm. S. Casselberry, Long Beach,
Calif.

Application May 15, 1950, Serial No. 9,954

Term of patent 14 years

(Cl. D53—13)

To all whom it may concern:

Be it known that I, Lee S. Mytinger, a citizen of the United States, residing at Long Beach, State of California, have invented a new, original, and ornamental Design for a Transparent Capsule and Tablet Pocket Carrier, of which the following is a specification, reference being had to the accompanying drawing, forming a part hereof.

Figure 1 is a plan view of a transparent capsule and tablet pocket carrier, showing my new design;

Figure 2 is an end view of the pocket carrier taken on the line 2—2 of Figure 1;

Figure 3 is a side elevational view of the device taken on the line 3—3 of Figure 1;

Figure 4 is a plan view of the pocket carrier with the slidably mounted cover in a partially open position; and

Figure 5 is a perspective view of the cover.

I claim:

The ornamental design for a transparent capsule and tablet pocket carrier, as shown and described.

LEE S. MYTINGER.
